UNITED STATES PATENT OFFICE.

ALBERT SCHMIDT, OF FLINT, MICHIGAN, ASSIGNOR TO CHAMPION IGNITION COMPANY,
OF FLINT, MICHIGAN, A CORPORATION OF MICHIGAN.

SPARK-PLUG.

1,155,514.

Specification of Letters Patent.

Patented Oct. 5, 1915.

Application filed March 16, 1912. Serial No. 684,115.

To all whom it may concern:

Be it known that I, ALBERT SCHMIDT, a citizen of the Republic of France, residing at Flint, in the county of Genesee and State 5 of Michigan, have invented certain new and useful Improvements in Spark-Plugs, of which the following is a specification, reference being had therein to the accompanying drawings.

10 The invention relates to spark plugs and has special reference to the construction of the electrode or sparking point which is grounded on the metallic case. Heretofore these electrodes have been usually formed 15 of wire of uniform cross section and which is easily bent out of place. Furthermore, as this wire is exposed to the heat of explosion and the heat conducting section is small the metal is frequently burned.

20 It is the object of the present invention to obtain a more substantial, rigid and heat insulating electrode and to this end the invention consists in the construction as hereinafter set forth.

25 In the drawings, Figure 1 is a perspective view of the spark plug casing and electrode detached; Fig. 2 is a cross section through the case with the electrode secured thereto; Fig. 3 is a similar view with the section at 30 right angles to Fig. 2 and showing the electrode in elevation; Fig. 4 is a plan view; Fig. 5 is an enlarged section through the joint; Fig. 6 is a longitudinal section through the case before the completion of the same; 35 and Fig. 7 is a cross section of Fig. 6 after the completion of the same.

A is the metallic casing of the plug provided with the usual threaded portion for engaging the threaded apertures in the engine casing, B, B' are lugs at the end of the casing A having a notch C therebetween, D is the contact point or electrode which is formed of a sheet metal stamping and is provided with a shank E for fitting into the

notch C with shoulders F for engaging the 45 lugs B, and B'. The member D is preferably formed of a tapering shape with a comparatively wide shank or base portion gradually diminishing in width toward the point. This not only contributes a greater 50 element of mechanical strength and rigidity but also is favorable for conducting away the heat from the point of the electrode and distributing it into the body of the case. The electrode is secured in position by first 55 engaging the shank in the notch C and then riveting over the projecting lugs B and B' on opposite sides of the notch as shown in Fig. 5. The electrode is then bent to extend over the end of the plug with its point in 60 proper relation to the coöperating electrode.

For convenience in manufacture, the casting A is first formed with an integral disk H extending completely across the lower end thereof. This disk is then struck out by a 65 suitable die to remove all portions thereof with the exception of the lugs B and B' as shown in Fig. 7.

What I claim as my invention is:

1. In a spark plug, the combination with 70 the case, of spaced lugs on said case, an electrode formed of a tapering sheet metal stamping having a shank engaging said spaced lugs and secured thereto by the riveting over of the latter.

2. In a spark plug, the combination with 75 the case, of an electrode formed of a tapering sheet of metal stamping having a shouldered shank portion, and spaced lugs on said case for receiving said shank and engaging said shoulder, said lugs being riveted over the shank to secure the same.

In testimony whereof I affix my signature in presence of two witnesses.

ALBERT SCHMIDT.
